CLEARER FOR ROVING OR SPINNING FRAMES

James L. Truslow, Whitinsville, and Henry L. Thomas, East Douglas, Mass., assignors to Whitin Machine Works, Whitinsville, Mass., a corporation of Massachusetts

Application April 2, 1942, Serial No. 437,384

5 Claims. (Cl. 19—149)

This invention relates to roving or spinning frames in which roving is drafted between drawing rolls or between long-draft aprons. In such machines, lint or fly adheres to the rolls or aprons and must be continuously collected and removed.

Both fixed clearers and freely rotating clearers have been used for this purpose but without complete success. Bunches of fly and lint gradually accumulate on the fixed clearers, which bunches are frequently dislodged and enter the roving or yarn. On the other hand, the freely rotating clearers have no scraping nor frictional action and will not remove closely adhering lint or fly, particularly from long-draft aprons.

It is the general object of our invention to provide a clearer for such purposes which will combine the good features of both fixed and rotating clearers and which will be more effective than either type of clearer.

To the accomplishment of this general object, we provide a clearer roll which is alternately fixed and rotated. We also provide improved and novel devices to produce this alternative and intermittent operation.

Our invention further relates to certain arrangements and combinations of parts which will be hereinafter described and more particularly pointed out in the appended claims.

Preferred forms of the invention are shown in the drawing, in which

Fig. 1 is a front elevation of a part of a drawing roll having our improved clearer associated therewith;

Fig. 2 is an enlarged sectional end elevation, taken along the line 2—2 of Fig. 1, and

Fig. 3 is a sectional side elevation showing our improved clearer associated with long-draft mechanism.

Referring to Figs. 1 and 2, we have shown a portion of a lower or driven drawing roll 10 having the usual fluted portions 11 by which the drafting is performed in association with the usual cushioned top rolls.

Our improved clearer roll R comprises a roller 15 having gudgeons 16 in its opposite ends and provided with cushioned or fabric-covered clearer portions 17, each of which portions may engage two of the fluted drawing roll portions 11. The gudgeons 16 are supported in vertically yieldable bearings by which the clearer roll R is pressed against the drawing roll 10.

These yieldable bearings may be in the form of U-shaped springs 20, as shown in Fig. 3, the

5 lower end of each being fixed to a stationary part at 21 and the upper end of each being bent to form an open bearing for a gudgeon 16. All of the construction thus far described is of the usual kind provided for freely rotating clearers.

We additionally provide the clearer roll R with a plurality of angularly spaced pins 25 which co-act with a ring or band 26 mounted on the drawing roll 10 between two fluted portions 11 and having a notch 27 at one point in its periphery. The band 26 rotates with the drawing roll 10 and is of such diameter that the outside of the band normally engages one of the pins 25 as shown in Fig. 2 and prevents 15 rotation of the clearer roll, which thus remains fixed during the greater part of each revolution of the drawing roll 10.

When the notch 27 reaches the pin 25 which is in engagement with the band 26, the clearer 20 roll will be advanced one space and until the next pin 25 engages the band 26. The clearer roll R is thus alternately fixed and rotated, and each intermittent advance movement presents 25 a fresh cushioned or fabric surface to the drawing roll, thus effectively removing the lint or fly therefrom.

In actual operation our improved clearer has 30 proved very effective and satisfactory, as it possesses sufficient frictional contact to remove all of the lint and fly from the drawing roll. It is also advanced intermittently, thus firmly pressing the accumulated lint or fly against the roll and preventing dislodgement thereof to pass into the roving or yarn.

In Fig. 3 we have shown our improved clearer embodied in a long-draft apparatus comprising 35 front rolls F and F', middle rolls M and M' and back rolls B and B'. A lower apron A and an upper apron A' are mounted on the middle 40 rolls M and M' and pass around the usual fixed guide bars 40. Our improved clearer roll R' engages the lower surface of the lower or driven back roll B and the outer surface of the lower apron A and thus frictionally removes the lint 45 and fly on both of these surfaces during the periods in which it is held from rotation. The means for intermittently advancing the clearer roll R' may be the same as is shown in Figs. 1 and 2 for the roll R.

The ring 26 may be formed integral with the 50 drawing roll 10 or may be attached thereto in any convenient manner, as by the two-part assembly construction shown in the prior patent to Brouwer, No. 1,998,729.

Having thus described two embodiments of our

invention, we do not wish to be limited to the details herein disclosed otherwise than as set forth in the claims, but what we claim is:

1. In a roving or spinning frame, a drawing roll continuously rotated in one direction, a clearer roll rotatably associated therewith and rotated thereby with the engaging portions of said rolls moving in the same direction, and means to positively and intermittently hold said clearer roll from rotation with said drawing roll 10 for successive predetermined intervals while said drawing roll continues to rotate.
2. In a roving or spinning frame, a driven drawing roll, a clearer roll associated therewith, a notched band on said drawing roll, a 15 plurality of circumferentially spaced pins on said clearer roll positioned to be engaged and intermittently and alternately held and advanced by said notched band.
3. In a roving or spinning frame, a drawing roll continuously rotated in one direction, a clearer roll in direct and positively driving contact with said drawing roll and rotated therewith, and means to positively and periodically interrupt the rotation of said clearer roll by said 20 drawing roll.
4. In a roving or spinning frame, a driven

5 drawing roll continuously rotated in one direction, a long-draft apron mounted thereon and actuated thereby, a clearer roll, means to cause said clearer roll to yieldingly engage said apron, and intermittently operating driving connections between said drawing roll and said clearer roll through which said clearer roll is given successive and positive intermittent advance movements in the same surface direction as that part of said apron engaged therewith and definite and positive intervening rest periods.

5. In a draft mechanism for textile fibers, the combination of two pairs of drawing rolls both positively and continuously rotated in one and the same direction, long-draft aprons on one pair of said drawing rolls, a clearer roll engaging the lower apron and the other lower drawing roll, and means to give said clearer roll successive positive but intermittent rotative motions in the same surface direction as that part of said apron engaged thereby and intervening positive rest periods, said clearer roll being thereby rendered effective to wipe the working surfaces of said lower apron and said second lower drawing roll.
